JAMES J. DAWSON, OF MCKEESPORT, PENNSYLVANIA.

DRIVE MECHANISM FOR MOVING-PICTURE MACHINES.

1,184,082.

Specification of Letters Patent.

Patented May 23, 1916.

Application filed September 21, 1914. Serial No. 862,695.

To all whom it may concern:

Be it known that I, JAMES J. DAWSON, a citizen of the United States of America, residing at McKeesport, in the county of Allegheny and State of Pennsylvania, have invented certain new and useful Improvements in Drive Mechanism for Moving-Picture Machines, of which the following is a specification, reference being had therein to the accompanying drawing.

This invention relates to a drive mechanism for moving picture machines and has for its object to provide a mechanism of such class, whereby a plurality of moving picture machines can be alternately operated or driven from a common drive element.

A further object of the invention is to provide a drive mechanism for moving picture machines which is simple in its construction and arrangement, strong, durable, efficient and convenient in its use, readily set up, and comparatively inexpensive to manufacture.

With the foregoing and other objects in view the invention consists of a novel construction, combination and arrangement of parts, as hereinafter more specifically described and illustrated in the accompanying drawings wherein is shown an embodiment of the invention, but it is to be understood that changes, variations and modifications can be resorted to which come within the scope of the claims hereunto appended.

In the drawings wherein like reference characters denote corresponding parts throughout the several views:—Figure 1 is a top plan view of a drive mechanism in accordance with this invention. Fig. 2 is a front elevation. Figs. 3 to 14 are details.

Referring to the drawings in detail the mechanism comprises a frame formed of a longitudinally extending member 1, and a pair of inclined members 2, 3, which extend from the ends of the member 1 and abut against each other. The members 2, 3, project in opposite direction but extend at an outward inclination with respect to the member 1 and said members 2, 3, have their inner ends abut at a point opposite the transverse center of the member 2. The frame further includes a pair of uprights 4, 5, which are secured to the outer ends of the members 2, 3 and ends of the member 1. The members 1, 2, 3, and uprights 4, 5 are constructed preferably of angle irons, and

the said members and uprights provide a supporting base.

Secured to the upper ends of the uprights 4, 5 is a pair of oppositely disposed T-couplings 6, 7, which are connected together by a longitudinal extending cylindrical bar 8, the latter being positioned parallel with respect to the member 1. Projecting forward from the couplings 6, 7, as well as being attached thereto, are cylindrical bars 9, 10, which have their forward ends provided with T-couplings 11. The couplings 11 carried by the bar 9 are oppositely disposed with respect to the couplings carried by the bar 10.

Secured to the meeting inner ends of the members 2, 3, is a vertically disposed Y-shaped supporting member 12, and which has each of its arms provided with a bearing 13 and extending through said bearing 13, as well as capable of revolving therein, is a shaft 14, having a groove drive pulley 15 fixed thereto and the said pulley 15 is operated by a suitable transmission, as illustrated a belt 16.

The shaft 13 has each of its ends provided with a female clutching member and the said members are indicated at 17, 18. Each of said clutching members 17, 18, has a portion of its length hollow to provide a bearing for the shaft. The shaft which associates with the clutching member 17 is indicated at 19 and the shaft which associates with the clutching member 18 is indicated at 20. Slidably mounted upon the shafts 19, 20, are male clutching members 21, 22, respectively. Each of the clutching members 21, 22, is provided with a longitudinally extending slot 23, and an annular groove 24. The shafts 19, 20, are provided with pins 25, which extend through the slots 23 whereby the members 21, 22 are slidably connected to the shafts 19, 20.

Adjustably secured to the shafts 19, 20, are collars 26 and interposed between these latter and the clutching members 21, 22, as well as surrounding the shafts 19, 20, are coil springs 27, the function of which is to normally shift the members 21, 22, to clutching engagement with the members 17, 18.

The shaft 19 is rotatably mounted in the couplings 11 carried by the bar 10 and the shaft 20 is rotatably mounted in the coupling 11 carried by the bar 9. Fixed to the shaft 19, as well as to the shaft 20, is a groove pulley 28, and each of said pulleys

has a suitable transmission, not shown, for a moving picture machine for driving it.

Associating with the clutching members 21, 22, is a shifting element therefor, and 5 which alternately moves the members 21, 22, in clutching engagement with the members 17, 18, that is to say, when the said element moves the member 21 in clutching engagement with the member 17, and the member 22 is 10 shifted for clutching engagement with the member 18. When the member 21 is in clutching engagement with the member 17, the shaft 19 is driven causing thereby the operation of the moving picture machine 15 which is driven from that pulley 28 carried by the shaft 19 and when the member 22 is clutched to the member 18 the shaft 20 will be operated causing that moving picture machine which associates with the pulley 28, 20 carried by the said shaft 20 to be actuated. The shifting elements consist of a pair of arms 29, 30, and each of which is provided with a yoke 31. The yoke of the arm 30 engages in the groove 24 of the member 21 25 and the yoke of the arm 29 engages in the groove 24 of the member 22. The arms 29, 30, are connected together by tie members 32, 33, and said arms 29, 30, are slidably mounted upon the cylindrical bar 8. The 30 shifting element is operated through the medium of a handle bar 34, which is fixed as at 35 to the arm 30, which passes through a guide 36 carried by the bar 10 and is provided with a handle 37.

35 What I claim is:—

1. A drive mechanism for a plurality of moving picture machines comprising a support, a drive element journaled in said support and provided with a pair of fixed hollow clutching members, said members projecting from the ends of said element, driven shafts having their inner ends normally journaled in said clutching members, supporting elements arranged at the outer ends 40 of said support and having the outer ends of said driven shafts journaled therein, shiftable clutching means carried by said driven shafts near the inner ends thereof, means for operating a shiftable clutching member 45 projecting from the ends of said element, driven shafts having their inner ends normally journaled in said clutching members, supporting elements arranged at the outer ends of said support and having the outer ends of said driven shafts journaled therein, shiftable clutching means carried by said driven shafts near the inner ends thereof, means for operating a shiftable clutching member 50 whereby it will couple with a fixed clutching member causing the operation of a driven shaft, and a transmission element carried by each of said driven shafts.

50 2. A drive mechanism for a plurality of

moving picture machines comprising a support, a drive element journaled in said support and provided with a pair of fixed hollow clutching members, said members projecting from the ends of said element, driven shafts having their inner ends normally 55 journaled in said clutching members, supporting elements arranged at the outer ends of said support and having the outer ends of said driven shafts journaled therein, shiftable clutching means carried by said driven shafts near the inner ends thereof, means for operating a shiftable clutching member 60 whereby it will couple with a fixed clutching member causing the operation of a driven shaft, and a transmission element carried by each of said driven shafts, and means mounted upon each of the driven shafts and engaging with the shiftable clutching member 65 carried thereby for normally forcing it toward the fixed clutching member carried by 70 the driven shaft.

3. A drive mechanism for a plurality of moving picture machines comprising a support, a drive element journaled in said support and provided with a pair of fixed hollow clutching members, said members projecting from the ends of said element, driven shafts having their inner ends normally 75 journaled in said clutching members, supporting elements arranged at the outer ends of said support and having the outer ends of said driven shafts journaled therein, shiftable clutching means carried by said driven shafts near the inner ends thereof, means for operating a shiftable clutching member 80 whereby it will couple with a fixed clutching member causing the operation of a driven shaft, and a transmission element carried by each of said driven shafts, and means mounted upon each of the driven shafts and engaging with the shiftable clutching member 85 carried thereby for normally forcing it toward the fixed clutching member carried by the driven shaft, and said driven shafts being arranged in longitudinal alinement with 90 respect to each other and with respect to said drive element.

In testimony whereof I affix my signature in the presence of two witnesses.

JAMES J. DAWSON.
